UNITED STATES PATENT OFFICE.

FRANK H. BROWN AND FRED H. BROWN, OF PORTLAND, OREGON.

UNLOADING APPARATUS.

No. 901,949.

Specification of Letters Patent.

Patented Oct. 27, 1908.

Application filed January 22, 1908. Serial No. 412,214.

To all whom it may concern:

Be it known that we, FRANK H. BROWN and FRED H. Brown, citizens of the United States, residing at Portland, in the county 5 of Multnomah and State of Oregon, have invented new and useful Improvements in Unloading Apparatus, of which the following is a specification.

This invention relates to an unloading apparatus which has been particularly devised 10 for use in relieving open cars or other analogous vehicles of their loads with convenience and expedition.

The apparatus is portable and readily reducible to compact form for movement from 15 one position to another, and may be easily disposed adjacent to a car or other vehicle and quickly arranged for operation.

One of the most essential characteristics of 20 this unloading apparatus is that the receptive extremity will follow the level of a load in a car or other vehicle to facilitate the engagement thereof with bags, boxes and other parcels without requiring the operator to 25 lift the bags, boxes or other devices up to the receptive extremity of the apparatus.

Another advantage is the expedition with 30 which bags, boxes and other parcels may be handled at the delivery extremity of the apparatus, especially in transferring such devices to a truck or analogous conveying means.

The invention consists essentially of a 35 portable stand carrying a motive means and having a conveying organization movably attached thereto and freely adjustable to different elevations.

The invention also consists in the details 40 of construction and arrangement of parts which will be more fully hereinafter specified.

In the drawings: Figure 1 is a perspective view of an unloading apparatus embodying the features of the invention and 45 shown applied. Fig. 2 is a transverse vertical section through a portion of a car and the conveying organization of the apparatus and the support for the stand of the apparatus, the stand being illustrated in side elevation and partially broken away. Fig. 3 is a detail plan view of a portion of the apparatus partially shown in section. Figs. 4, 5, 6 and 7 are detail views of parts of the apparatus.

55 Similar characters of reference are em-

ployed to indicate corresponding parts in the views.

The numeral 1 designates a stand, comprising essentially a base frame 2, having casters 3, uprights 4, holding a platform 5, inclined side supports 6 which are projected beyond the one end of the stand, and uprights 7 connected to the side supports and the base frame 2. The inclined supports 6 have a chute member or plate 8 confined therebetween and coinciding at its lower extremity with the rear end of the platform 5. The angle of inclination of the chute member or plate 8 is different from that of the supports 6, so as to coöperate with the platform 5 in the delivery of bags, boxes or parcels to the said platform with less abruptness, and also to have a part of the upper surface of the said chute member or plate elevated above the adjacent edges of the supports 6 to prevent contact and obstruction to movement of bags, boxes or parcels delivered over the said chute member and facilitate the direction of such bags, boxes or parcels fully on to the platform 5. The frame of the stand as described also serves to conveniently support a motor 9 which, in the present instance, is shown of the gasoline type, though it will be understood that any suitable motor may be employed. It is preferred that the complete motor be disposed within the stand 1 to carry out the idea of portability of the apparatus, and to avoid dependence on driving power at a distance from the apparatus to effect an actuation of the conveying means 90 which will be presently described. The motor 9 actuates the driving shaft 10 held in suitable bearings on the uprights 7.

The foregoing organization forming part of the apparatus comprises an elevator frame 11, made up of upper and lower angle irons 12 and 13, forming tracks and connected by side lattice work 14, to give lightness and strength to the structure. The horizontal flanges of the angle irons 12 and 13 are directed inwardly and are engaged by rollers 15 on the opposite extremities of a plurality of shafts 16, the latter being preferably rectangular in cross section to present flat surfaces for the reception of bags, boxes and other parcels. The shafts 16 are arranged at regular intervals and connected to chain belts 17, these belts being secured in such manner to the shafts that when the complete conveyer comprising the shafts and belts is 110

in operation, the upper surfaces of the shafts traveling over the upper portion of the conveying apparatus will be free to receive bags, boxes or other parcels. The chain belts 17 travel over or engage the sprocket wheels 18 on a shaft 19, having bearing in the upper ends of the supports 6, and also travel around and operatively engage sprocket wheels 20 at the opposite extremities of a drum 21 rotatably disposed in the receptive end of the conveying apparatus, as clearly shown by Fig. 2. A partition 22 is held between the side members of the elevator frame and adjacent the upper angle irons 12 so as to prevent the bags, boxes or other parcels engaging the several shafts 16 from projecting downwardly and interfering with the operation of the portions of the endless chain belts 17 below. The partition 22, therefore, serves as a guard and extends almost the full length of the conveying organization, as clearly shown by Fig. 2. The shaft 19 is free to rotate in the upper ends of the supports 6 and to thus serve as a fulcrum means for the conveying organization without in the least modifying its function as a driving element for the endless chain belts 17 and shafts 16. The driving shaft 10 is provided with a sprocket wheel 23, and the adjacent end of the shaft 19 has a sprocket wheel 24 keyed thereto and of larger diameter than the said sprocket wheel 23. Around the sprocket wheels 23 and 24 is a chain belt 25 engaged by a belt tightener consisting of a small sprocket wheel 26 supported on the rear end of an arm 27 adjustably secured to one of the supports. The sprocket wheel 23 in its operative relation to the shaft is controlled by a suitable clutch 28, having an upper standing shifting lever 29, whereby the conveying apparatus may be set in motion or stopped as may be desired, without affecting the motor 9.

From the foregoing it will be understood that the conveying organization is freely movable or has a fulcrumed connection with respect to the stand 1, through the medium of the shaft 19 engaging the upper ends of the supports 6, by means of devices which will be hereinafter described, the object of this association of the parts mentioned being to permit the conveying apparatus to be raised or gravitate in relation to the height of the load, and thus facilitate the application to the receptive extremity of the conveying apparatus of bags, boxes or other parcels contained within a car or other open vehicle. This adjustment of the conveying apparatus may be carried on without in the least affecting the association of the driving mechanism, and when the apparatus is not in use the conveying organization may be thrown over on the top portion of the stand for convenience in transportation of the complete apparatus.

There are many mechanical means for applying the shaft 19 to the ends of the supports 6, but it has been found by experiment that the most efficient devices for this purpose consist of boxes 30, having outer flanges 31 projected through the ends of the supports 6 and formed with inner shouldered bearing extremities 32, and through these boxes the opposite extremities of the shaft 19 extend. The outer flanges 31 of the boxes 30 are suitably secured against the outer sides of the supports 6, and the inner bearing extremities 32 are engaged by eyes 33 of coupling members 34 secured to the adjacent extremities of the opposite sides of the lifting frame of the conveying organization, as clearly shown by Figs. 3, 4, 5, 6 and 7. The coupling members 34 embody shanks 35 on which the eyes 33 are formed, and said shanks are secured by clips 36 bolted or otherwise secured to the adjacent extremities of the opposite sides of the elevator frame. By the use of these coupling members the conveying organization may be swung in opposite vertical directions without interfering in the least with the shaft 19.

The operation of the improved unloading apparatus is very simple. After the conveying organization has been properly disposed in a car or other vehicle to be unloaded, the motor is started and the conveyer proper actuated to cause the chain belts 17 and shafts or bars 16 to move towards the upper ends of the supports 6. Bags, boxes or other parcels containing the material to be unloaded are individually placed on the receptive end of the conveying organization so as to engage at least one of the shafts or bars 16, the following shaft or bar engaging a portion of the bag, box or parcel as it comes around into proper position to thus insure coöperation of a pair of the shafts in elevating the bags or other devices. The receptive extremity of the conveying organization is so shaped that it may bear on the bottom of a car or vehicle without interfering with the operation of the chain belts and shafts or bars 16. When the bags or other devices arrive at the upper ends of the supports 6 they are caused to engage and slide downwardly over the chute member or plate 8 on to the platform 5, and fall with such rapidity on to the platform that an operator may grasp the moving bag or other device and with very little exertion direct it over on to a truck or other device disposed adjacent the stand, or the bags, boxes or parcels gravitating over the chute member 8 on to the platform 5 may be stacked or otherwise disposed at one side of the stand. From time to time the stand and conveying organization may be shifted longitudinally with respect to the car or other vehicle being unloaded to bring the receptive end of the conveying organization

in more convenient position with relation to the bags, parcels or other devices remaining in the car or vehicle.

Between the attached end of the conveying organization and the upper extremity of the chute member a roller 37 is mounted on the shaft 19 between the sprocket wheels 18, the roller being of such diameter or having a projection relatively to the adjacent parts that the packages, parcels or boxes delivered from the conveying organization will be positively directed to the chute member 8 by engaging the said roller 37. This roller is an advantageous addition to the general construction of the apparatus, but it will be understood that its use is not necessarily essential in view of the fact that the attached end of the conveying organization may be drawn as close as may be desired to the upper end of the chute member. Therefore, it may be said that the roller 37 is an intermediate guiding means for directing the bags or parcels from the conveying organization to the chute member.

25 The improved unloading apparatus may also be used for transferring the contents of one bin to another bin, or for other purposes where it may be found applicable, and by its use the operation of unloading may be carried on with great expedition.

Having thus described the invention, what is claimed, is:

1. In an unloading apparatus, the combination of a portable stand having a flat platform, an upwardly inclined chute member coöperating with said platform, and a conveying organization movably held adjacent to the upper end of the chute member and adjustable to different vertical planes.
2. In an unloading apparatus, a portable stand having a platform, a conveying organization movably connected at one end to the stand above the platform and adjustable to different elevations, means between the connected end of the conveying organization and the platform for directing bags, parcels and the like to the said platform, and motive means carried by the stand for actuating the conveying organization.
3. In an unloading apparatus, a portable stand having a horizontal platform, a conveying organization movably connected at one extremity to the upper portion of the stand and adjustable at its free end to different elevations, means between the connected extremity of the conveying organization and the platform for delivering bags, parcels and the like to the said platform, and means for actuating the conveying organization.
4. In an unloading apparatus, a portable stand having a receptive platform, a conveying organization movably connected at one extremity to a portion of the stand above the platform, and means between the

connected extremity of the conveying organization and the platform to deliver parcels, bags and the like to the said platform.

5. In an unloading apparatus, a portable stand having a receptive platform, a conveying organization movably connected at one extremity to a portion of the stand above the platform and having its free end adjustable to different elevations, the conveying organization being foldable over on the stand, means between the platform and conveying organization for directing parcels, bags and the like from the conveying organization to the platform, and a complete operating mechanism carried by and movable with the stand for actuating the conveying organization.

6. In an unloading apparatus, a portable stand having a receptive platform, an inclined chute member extending upwardly from the platform, a conveying organization movably connected at one extremity to a portion of the stand above the platform and chute member and having its free end adjustable to different elevations, and a guiding member between the connected extremity of the conveying organization and the upper end of the chute member.

7. In an unloading apparatus, a portable stand having a receptive platform, an upwardly inclined fixed chute member coöperating with said platform, and a conveying organization movably connected at one extremity to the upper portion of the stand above the platform and chute member and having its free extremity adjustable above the stand and also below the latter, the conveying organization being disposed to deliver bags, parcels and the like to the chute member.

8. In an unloading apparatus, a portable stand having upwardly projecting inclined supports, a platform, and an inclined chute member between the supports, and a conveying organization fulcrumed to the upper ends of the supports and adjustable to different elevations.

9. In an unloading apparatus, a portable stand, and a conveying organization fulcrumed to one extremity of the said stand and comprising a plurality of transverse shafts with rollers on opposite extremities and chain belts conencted to said shafts, the shafts having flat surfaces to engage bags, parcels and the like.

10. In an unloading apparatus, a portable stand having a receptive platform and means for delivering bags, parcels and the like to the platform, a motor and drive shaft mounted within the stand, and a conveying organization movably attached at one end to the upper portion of the stand and adjustable at its free end to different elevations, the conveying organization having an operating connection with the said drive shaft.

11. In an unloading apparatus, a portable stand having a platform and a chute member terminally coinciding, the platform being unobstructed for quick removal of bags, 5 parcels or the like therefrom, and a conveying organization fulcrumed to the stand adjacent the upper end of the chute member and adjustable to different elevations.
12. In an unloading apparatus, a portable stand having a platform and a chute member projecting upwardly therefrom, and a conveying organization fulcrumed to the stand adjacent the upper end of the chute member and embodying a conveyer to deliver bags and other parcels to the said chute member, the conveying organization being adjustable to different elevations.
13. In an unloading apparatus, a portable stand having a fixed platform, a conveying organization fulcrumed at one extremity to the upper portion of the stand and projectable over and downwardly into an open car or other vehicle below the platform, and means interposed between the attached extremity of the conveying organization and the fixed platform for directing bags, boxes or the like from the conveying organization to the platform.
14. In an unloading apparatus, a portable stand having a fixed platform and a stationary chute member rising at an inclination from the said platform, motive means and a drive shaft carried by said stand, a shaft held by the stand above the upper end of 35 the chute member and operatively connected to the said drive shaft, and a conveying organization embodying a movable conveying element actuated by the shaft above the upper end of the chute member, the said conveying organization being attached at one extremity to the shaft held by the upper portion of the stand and having its free end adjustable to different elevations.
15. In an unloading apparatus, a stand having supports projecting upwardly therefrom, a chute member between the supports, 40 a shaft in the upper extremities of the supports, a conveying organization, and coupling members connected to the conveying organization and movably engaging around the said shaft to permit said conveying organization to be freely moved to different elevations.
16. In an unloading apparatus, a portable stand having a chute member, a shaft disposed above the said chute member, bearing boxes for the shaft having inwardly projecting reduced bearing extremities, a conveying organization, coupling members connected to the conveying organization and 50 engaging the said bearing extremities of the boxes to permit said organization to be adjusted to different elevations, and means carried by the stand for operating the said shaft and the movable parts of the conveying organization.
17. In an unloading apparatus, a stand, a chute member held by the stand, and a conveying organization or carrier movably connected to the stand and freely adjustable 55 without modifying the condition of the chute member, the conveying organization or carrier having its delivery extremity disposed to coöperate with the upper extremity of the chute member.
18. In an unloading apparatus, a portable stand having a chute member, and a conveying organization or carrier movably connected at one extremity to the stand and disposed to coöperate with the upper extremity 60 of the chute member and freely adjustable without modifying the position of the chute member.
